UNITED STATES PATENT OFFICE.

JOHN R. REYNOLDS, OF HARTFORD, CONNECTICUT, ASSIGNOR TO THE SMYTH MANUFACTURING COMPANY, OF HARTFORD, CONNECTICUT, A CORPORATION OF CONNECTICUT.

FORMER FOR SHAPING THE BACKS OF BOOK-COVERS.

1,323,319.

Specification of Letters Patent.

Patented Dec. 2, 1919.

Application filed June 21, 1919. Serial No. 305,856.

To all whom it may concern:

Be it known that I, JOHN R. REYNOLDS, a citizen of the United States, residing at Hartford, in the county of Hartford and 5 State of Connecticut, have invented a new and useful Improvement in Formers for Shaping the Backs of Book-Covers, of which the following is a specification.

A book cover or case has two more or less 10 stiff sides commonly made of paper or pulp board, connected by a back which is usually a strip of cloth or cloth lined with paper, in such manner that the joints between the edges of the sides and the back will be flexible and allow the book to open easily.

This invention relates to the formers 15 which are used in machines provided to set into the desired shape the backs of such covers. A machine of this class is illustrated and described in U. S. Letters-Patent No. 1230292, issued June 19, 1917, on the application of James C. Gourley.

Books vary greatly in thickness, their 20 back edges differ in shape, and the cover backs extend around the back edges of different books to a greater or less degree. Consequently provision must be made for different widths of backing material between the creasers, which together with the 25 former shape the cover backs and insure the flexible joints at the correct localities.

The object of this invention is to provide 30 for machines of this type a former which is adjustable in thickness, and thereby obviate the necessity of having a large number of 35 formers of various dimensions for correctly shaping the backs of cases for the many different sizes of books.

In the accompanying drawings a former 40 embodying this invention is illustrated as designed for application to a machine of the character set forth in the patent referred to. Figure 1 shows a plan of the former and so much of the related mechanism of 45 such a machine as is necessary to an understanding of the construction and use of the improvement. Fig. 2 shows on larger scale a transverse section of the former and related mechanisms with a book cover having 50 its back shaped thereby, on the plane indicated by the dotted line 2-2 on Fig. 1. Fig. 3 shows an enlarged plan of the former. Fig. 4 is a side view of the same. Fig. 5 shows a plan of one end of the former with 55 parts cut away. Fig. 6 is a transverse sec-

tion on the plane indicated by the dotted line 6-6 on Fig. 3. Fig. 7 is a transverse section on the plane indicated by the dotted line 7-7 on Fig. 3.

In the machine illustrated the covers are 60 stacked between the walls 1 of the magazine and one at a time successively removed from the bottom of the magazine by feed blocks 2 attached to feed chains 3 which pass around sprocket wheels 4 mounted at the ends of the 65 machine. The feed blocks engage the top or bottom edges of the stiff sides 5 of the lowest cover in the stack and push it out of the magazine, carrying it along the machine bed 6 with the stiff sides held down by bars 70 7 and with the outer edges of the cover sides resting upon the supporting bars 8 which are provided with guide wings 9 adjusted so as to crowd the sides of the cover together and give the cover back 10 the necessary 75 amount of slack required for its formation. As the stiff sides of the cover are pushed by the feed blocks along the supporting bars between the guide wings and beneath the 80 holding down bars, the back passes onto the former 11 which increases in size to that which will give the back the desired shape. At the same time the back passes between the creasers 12 which put the creases into the back at the joints between the back and 85 sides and hold the back tightly stretched over the former in order to set it in the required shape. Figs. 1 and 2.

The former which is the subject of the 90 present invention comprises a bar 13 that is mounted upon the machine bed below the creasers. This bar has in its upper face transversely extending T-shaped slots 14. Movable transversely on the top of the bar are gibs 15 which have inwardly extending 95 under-cut flanges 16. Screws 17 pass through these gibs into T-shaped blocks 18 which are loosely fitted in the transverse slots in the top of the bed bar. If the screws are loosened the gibs may be moved 100 toward and from each other, being guided by the blocks in the slots in the bed bar. When the screws are tightened the gibs are drawn down closely to the top of the bar and are held in place against movement.

The former plates 19 are arranged so as to extend upwardly parallel with each other between the gibs. The lower edges of the former plates rest upon the top of the bed bar. The former plates have outwardly ex- 110

tending shoulders 20 which are inclined to fit the under-cut faces of the flanges on the gibbs. When the gibbs are freed by loosening the binding screws and they are 5 adjusted toward or from each other, the former plates are carried with them. When the gibbs are secured by tightening the screws the former plates are held firmly in the positions to which they have been moved, 10 along their whole length by the engagement of the under-cut gib flanges with the inclined shoulders on the outside of the lower edges of the former plates. This method of securing the former plates holds them 15 always upright and parallel.

For the purpose of adjusting these parts toward and from each other when the screws are loosened, near each end between the former plates is a rotatable arbor, the lower 20 end 21 of which extends into a socket in the bed bar while the upper end 22 has a slot by means of which the arbor may be rotated. The inner faces of the former plates are slightly cut away around these arbors 25 to facilitate the entrance of a screw driver or other means by which the arbor may be turned. Secured on each arbor, just above the top face of the bed bar and between the lower edges of the former plates, is a block 30 23 that is somewhat longer than it is wide. By turning the arbors and these blocks the former plates and gibbs may be moved outwardly so that the plates will be spread to just the required width for properly shaping 35 the back of the cover, this width, of course, depending on the thickness and shape of the back edge of the book to which the cover is to be applied. In order to adjust the parts, the screws which hold the gibbs 40 are slightly loosened, then the arbors are turned so as to separate the former plates to the required degree, after which the gib screws are tightened. The entrance end 24 of the former plates is slightly tapered so 45 as to permit the back of the cover to slide on freely without obstruction from the ends of the plates.

The invention claimed is:—

1. A former for shaping the backs of book 50 covers comprising a bed, upright former plates resting upon and slidably transversely

toward and from each other on the top of the bed, and means for securing the plates rigidly to the bed at the required distance apart.

55

2. A former for shaping the backs of book covers which consists of a bed, former plates mounted on the bed and movable thereon toward and from each other, means for separating the plates, and means for securing 60 the plates rigidly to the bed in their desired relation.

3. A former for shaping the backs of book covers comprising a bed, former plates movably mounted upon the bed and having outwardly extending shoulders, and gibbs adjustably mounted on the bed and having flanges engaging the said shoulders on the former plates.

4. A former for shaping the backs of book 70 covers comprising a bed, former plates movable toward and from each other upon the bed, gibbs adjustably mounted on the bed and adapted to engage the former plates, means for adjusting the plates and gibbs 75 toward and from each other, and means for securing the gibbs in position.

5. A former for shaping the backs of book covers comprising a bed, upright plates arranged parallel on the bed, rotatable arbors mounted upon the bed and extending between said plates, eccentric means on the arbors for separating the plates, and means for holding the plates in adjusted position.

6. A former for shaping the backs of book 85 covers comprising a bed, plates arranged upright on the bed, said plates having inclined shoulders on the outside of their lower ends, gibbs movably mounted on the bed and having under-cut flanges engaging the 90 inclined shoulders on the plates, means for securing the gibbs in place, and means for moving the plates and gibbs from each other.

7. A former for shaping the backs of book covers comprising a bed having transverse 95 under-cut slots in its upper face, blocks loosely fitting said slots, upright plates mounted parallel with each other upon the face of the bed, gibbs for engaging and holding said plates, and screws passing through 100 said gibbs into said blocks.

JOHN R. REYNOLDS.
